Primary Examiner — Daniel Bui*(74) Attorney, Agent, or Firm* — Locke Lord LLP(57) **CLAIM**

The ornamental design for a board-mount connector, as shown and described.

DESCRIPTION

FIG. 1 is a top perspective view of a board-mount connector showing our new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top elevation view thereof;

FIG. 7 is a bottom elevation view thereof; and,

FIG. 8 is a bottom perspective view thereof.

The broken line in the figure drawing views is included for the purpose of illustrating unclaimed environment only and forms no part of the claim designed. The dash-dot line in the figure drawing views represent the boundary of the claimed design.
